UNITED STATES PATENT OFFICE.

PHILIP V. BROWN, OF NEW YORK, N. Y.

DEVICE FOR WITHDRAWING BLOOD FROM THE BODY.

1,124,285.

Specification of Letters Patent. Patented Jan. 12, 1915.

Application filed May 28, 1912. Serial No. 700,202.

To all whom it may concern:

Be it known that I, PHILIP V. BROWN, a citizen of the United States, residing at New York, in the county of New York and State of New York, have invented new and useful Improvements in Devices for Withdrawing Blood from the Body, of which the following is a specification.

My invention relates to the withdrawal of samples of blood from the body for tests and consists in a simple device whereby this may be done conveniently and the sample then conveniently transported, if necessary, an indefinite distance to the laboratory.

15 The essential features of the device are a closed glass tube or receptacle of any convenient shape, within which a vacuum has been produced, a hypodermic needle and a suitable tubular connecting means, preferably flexible, between the receptacles and the needle. Means must be provided whereby communication may be established between the connecting means and the interior of the glass tube after the needle has been 20 inserted in the body, so that the blood sample may be drawn into the tube.

In the drawing herewith I have illustrated a simple and desirable form of device embodying my invention.

25 Figures 1 and 2 are longitudinal sections respectively before and after said communication has been established. Fig. 3 shows a slightly modified form of receptacle.

30 In the figures 1 indicates the glass receptacle for the blood, which may be merely a test-tube as indicated. A vacuum is created in this receptacle by any usual means and then closed either by sealing the end at 2 as shown in Fig. 3 or by inserting an air-tight rubber cork 3 provided with the short 35 glass tube or tip 4, whose end 5 is sealed in a gas flame after the vacuum has been established. This end should be slightly elongated so that it may be broken to make 40 connection between the vein and the receptacle after the needle has been inserted, as indicated in Fig. 2, whereby the blood is drawn from the body into the receptacle.

45 6 is the connecting means, preferably a rubber tube fitted over the closed end of the top 4, as shown in the figures and carrying in its other end the needle 7.

50 When the sample has been drawn into the receptacle, the rubber tube may be closed 55 air tight by means of a suitable clamp 8, but I much prefer to seal the tip at about

the point 9 by the flame, whereupon the rubber may be withdrawn and with it the broken end of the tip and the receptacle may then be transported in the pocket or by mail etc., to the laboratory.

The advantages of my device are its simplicity, economy and compactness. By its assistance it is a simple matter for any physician to obtain a sample of blood at any 60 distance from the laboratory to which it is then sent for the bacteriological or serum test. Heretofore blood tests have been inconvenient and difficult for it has been necessary to bring the patient to the laboratory where the expert could take the blood sample.

In Fig. 1 is indicated at 10 ammonium oxylate for preventing coagulation, where that is necessary, or some suitable culture 75 medium may be deposited in glass tube, but generally speaking the latter is not done for the culture is made at the laboratory. I prefer the form of tube shown in Figs. 1 and 2, closed by a rubber cork, for this may 80 be cleaned easily. By the old method there was danger of contamination; the blood was withdrawn by a syringe and was deposited in the various media at the bedside. All of which was complicated and inconvenient, 85 often frightening the patient and those implements were difficult to manipulate and to transport. Only a pathologist could practise those old methods; evidently they were almost impossible for the country physician, whereas with my device the blood can easily be withdrawn by any physician. This device is always ready and convenient and may be used, not only for blood tests, but to draw liquids from any part of the 90 body.

Having described my invention, I claim:

1. A simple, compact device for extracting blood from the body, comprising a small receptacle having a vacuum produced therein and provided with a single opening, a plug fitted thereto and having also a single opening therethrough, a hypodermic needle, a tubular connection between the needle and the plug forming a continuous channel from 105 the needle to the receptacle, means initially to maintain said channel closed while the needle is being inserted in the body and then to open the same, and means to close the same after the blood has been extracted. 110

2. As a new article of manufacture a device for the extraction of blood, comprising

a receptacle having a vacuum produced therein and provided with a glass neck adapted for the attachment of a connection from a hypodermic needle, said neck having 5 an elongated weakened seal portion to be inclosed within the connection and adapted to be broken therein without exterior exposure.

3. A simple, portable device for extracting 10 blood from the body and temporarily retaining the blood, comprising a small, glass receptacle having a single opening only, the same being the mouth of the receptacle, a plug fitted to said opening, said plug having a single perforation only extending therethrough and adapted to connect the interior of the receptacle with the exterior, a hypodermic needle, a tubular connection between the needle and the perforation forming a continuous channel from 15 the needle to the interior of the receptacle, means initially to close said channel, and then permitting the same to be opened when the needle has been inserted, and means to 20 close the same when the blood has been withdrawn.

4. A device of the character described 25 consisting of a receptacle having a vacuum produced therein, said receptacle having a

single open end, a stopper fitted to said end, 30 a single glass inlet tube carried by the stopper, a fused seal portion for said tube, a hypodermic needle and a flexible connection therefrom to the tube arranged to inclose the fused seal portion to permit breaking 35 of the seal therein without exterior exposure.

5. A device of the character described 40 consisting of a receptacle having a vacuum produced therein, said receptacle having an open end, a stopper fitted to said end, a glass inlet tube extended through said stopper, a fused seal portion for said tube, a hypodermic needle, a flexible connection 45 therefrom to the tube arranged to inclose the fused seal portion to permit breaking of the seal to establish a closed communication between the needle and receptacle and a suitable clamp to seal the connection after the seal has been broken.

50 In testimony whereof I have signed my name to this specification in the presence of two subscribing witnesses.

PHILIP V. BROWN.
